OF ONE-THIRD TO MAX FEDER, OF NEW YORK, N. Y.

WASHING-MACHINE.

1,243,413.

Specification of Letters Patent. Patented Oct. 16, 1917.

Application filed February 25, 1916. Serial No. 80,510.

To all whom it may concern:

Be it known that we, RICCARDO ISOBABELLA and FRANCESCO LOMBARDI, a subject of the King of Italy and a citizen of the United States, respectively, residing at New York, in the county of New York and State of New York, have invented new and useful Improvements in Washing-Machines, of which the following is a specification.

10 The invention relates to clothes washers, and it includes the novel features herein-after described and claimed.

An object of the invention is to provide a washer of simple and durable structure having means for lifting the clothes as they are passed through the washing liquid and means for beating the clothes, moving in a direction opposite to that in which the lifting means move while in operation.

20 In the accompanying drawing:

Figure 1 is a vertical longitudinal sectional view of our improved washer;

Fig. 2 is a transverse sectional view of the same cut on the line 2—2 of Fig. 1;

25 Fig. 3 is a similar view cut on the line 3—3 of Fig. 1;

Fig. 4 is a detail view of a modification used in the device;

Fig. 5 is a detail view of a modification 30 of the form of beater used in the device; and

Fig. 6 is a detail view of a lifter used in the device.

As illustrated in the accompanying drawing, the clothes washer includes a tank 1 which may be of any usual or desired shape. Said tank is provided with a draw valve 2.

Stub shafts 3 are journaled for rotation in the ends of the tank 1 and the said shafts are squared at their inner ends, as at 4.

40 Gear wheels 5 are mounted upon the shafts 3 and mesh with gear wheels 6 mounted upon stub shafts 7 also located at the ends of the tank 1. A crank shaft 8 is applicable to one of the stub shafts 7 and may be used for 45 rotating the same.

A receptacle is located within the tank 1 and is adapted to contain the clothes during the washing operation. The said receptacle includes heads 9 which are journaled upon the stub shafts 3 hereinbefore referred to. The said heads 9 are connected together by means of a foraminous material 10 which is in the form of wire mesh ma-

terial or any other suitable open-work material. The said foraminous material is in 55 sections and one section, for instance, the section 11, is hingedly or movably mounted whereby the interior of the receptacle which holds the clothes may be accessible for removing or placing clothes therein. The 60 heads 9 are provided upon their outer sides with annuli 11' which are provided at their inner and outer edges with sets of gear teeth, as best illustrated in Fig. 2 of the drawing. The gear wheels 5 which mesh 65 with the gear wheels 6 are adapted to transmit rotary movement to the receptacle of which the heads 9 and foraminous material 10 are components when the gear wheels 6 are rotated. The said gear wheels 6 also 70 mesh with the inner set of teeth of the annuli 11. A shaft 12 is journaled for rotation at the upper portion of the tank 1 and gear wheels 13 are mounted upon said shaft and mesh with the outer teeth of the 75 annuli 11'. Bars 14 are mounted in the receptacle of which the heads 9 are components and are spaced at suitable intervals apart.

Arms 15 are mounted upon the squared 80 ends 4 of the stub shaft 3 and rotate with the shafts. Inasmuch as the gear wheels 6 are interposed between the gear wheels 5 and the annuli 11', the said arms 15 are rotated in a direction opposite to that of the 85 receptacle of which the heads 9 are components when the said receptacle is rotated. A shaft 16 is carried by the arms 15 and a beater 17 is journaled on the said shaft. The said beater may be stellar-form in 90 transverse section or of any other configuration suitable for encountering the clothes and agitating or beating the same during the washing operation. A bar 18 is also carried by the arms 15 and serves as an additional beater to encounter the clothes in 95 advance of the action of the beater 17.

As shown in Fig. 1 of the drawing the bar 18 is provided at one end with a sleeve 19 in which is located a spring 20, which 100 normally holds the said sleeve distended with relation to the bar. When the sleeve 19 is inserted in the socket of the arm 15 the bar 18 is held in position. By retracting the sleeve 19, the spring 20 is compressed 105 and said sleeve may be removed from the

socket of that arm which receives it and hence the bar 18 may be disconnected from the arms 15.

In the modified form shown in Fig. 4 of the drawing, it will be observed that the arms 15 are provided with recesses 21 in which are located coil springs 22, the said springs bearing at one end against the shaft 16 and holding the said shaft toward the outer ends of the said recesses. Therefore, it is apparent that when the beater 17, which is journaled upon the shaft 16, encounters the clothes the said beater may move in an inward direction in the event that the clothes 15 are in a wad and should tend to choke or interfere with the operation of the machine.

As illustrated in Fig. 5 the beater 17 is provided at the intervals between its points with rifles 23 which may perform their function in washing or cleaning the clothes 20 while the device is in operation.

As shown in Fig. 6 the bar 14 may be provided with bristles 24 which also encounter the clothes and operate upon the same with a cleaning effect during the manipulation of the device.

From the foregoing description, taken in conjunction with the accompanying drawing, it will be seen that a clothes washing 30 device of simple and durable structure is provided and that the parts mutually co-

operate with each other to effectually and efficiently clean the clothes at an expense of small manual labor.

In using the structure very desirable and 35 beneficial results are obtainable by permitting the water in the boiler to come to a boiling point and then by simply revolving the clothes container occasionally or from time to time in the presence of the hot water 40 and steam, the water is made to pass through the clothes in somewhat film-like masses and the action resulting brings about both a thorough and rapid cleansing of the clothes.

Having thus described our invention, we 45 claim:

A clothes washer comprising a tank, a foraminous receptacle journaled for rotation in the tank, means for rotating the receptacle in one direction, a beater located within the receptacle, a detachable bar connected with the beater, and means for rotating the beater and the bar in a direction opposite to that in which the said receptacle rotates.

In testimony whereof we affix our signatures in presence of a witness.

RICCARDO ISOBABELLA.
FRANCESCO LOMBARDI.
